BUTTER CONTAINER

Richard B. Janes, Baldwin Lake, Mich., assignor
to Gibson Refrigerator Company, Greenville,
Mich., a corporation of Michigan

Application November 30, 1950, Serial No. 13,208

Term of patent 7 years

(Cl. D67—2)

To all whom it may concern:

Be it known that I, Richard B. Janes, a citizen of the United States, residing at Baldwin Lake, Greenville, county of Montcalm, and State of Michigan, have invented a new, original, and ornamental Design for a Butter Container, of which the following is a specification, reference being had to the accompanying drawing, forming a part thereof, in which:

Figure 1 is a perspective view of a butter container showing my new design; Fig. 2, a front view in elevation; Fig. 3, a side view in elevation; Fig. 4, a top plan view; and Fig. 5, a sectional view, the section being taken as indicated at line 5—5 of Fig. 2.

I claim:

The ornamental design for a butter container, as shown.

RICHARD B. JANES.
